UNITED STATES PATENT OFFICE.

EDWIN F. GUTH, OF ST. LOUIS, MISSOURI.

LAMP-RECEPTACLE.

1,147,717.

Specification of Letters Patent. Patented July 27, 1915.

Application filed January 21, 1915. Serial No. 3,426.

To all whom it may concern:

Be it known that I, EDWIN F. GUTH, a citizen of the United States of America, residing at the city of St. Louis, State of Missouri, have invented a certain new and useful Lamp-Receptacle, of which the following is such a full, clear, and exact description as will enable any one skilled in the art to which it appertains to make and use the same, reference being had to the accompanying drawings, forming part of this specification.

My invention relates to a receptacle or socket for electric lamps, its object being to provide a socket which shall combine the convenience and simplicity of what are known as "open terminal" sockets with the safety, in the matter of fire prevention, of "closed terminal" sockets.

Closed terminal sockets, as now constructed, usually comprise two or more parts, at least one of which must be removed to give access to the terminals, or, are of the form known as "pig-tail" sockets, in which short connecting wires are permanently fastened in the socket by means of fusible insulating material. Some of the disadvantages of these sockets, in addition to their increased cost, are that connection with the supply wires must be made by splicing and the joint then insulated, and that the connecting wires often break when bent adjacent to the socket, thus rendering the entire socket useless for further service. The objection to open terminal sockets resides in their danger as a source of fire, and the rules of fire underwriters require that receptacles having exposed terminals must not be used in canopies or fixtures unless completely inclosed in metal.

By means of my invention, I avoid the disadvantages of the prior closed terminal receptacles in the matter of the cost of construction and installation and, at the same time, secure the safety of such receptacles. By my invention, I also secure the relative cheapness of construction and simplicity of installation characteristic of the open terminal receptacle.

In the accompanying drawings, which illustrate one embodiment of my invention, Figure 1 is a plan view of my improved socket, and Fig. 2 is a view partly in cross section and partly in elevation.

The receptacle 1 is formed of porcelain or other suitable insulating material and is

provided with a lamp receiving socket 2 and relatively deep recesses or pockets 3 communicating at their bottom with the bottom of the lamp receiving socket. In the lamp socket is situated the usual threaded conducting shell 4 to which is electrically connected the contacting plate 5 which extends into one of the pockets 3. Another contacting plate 6 extends from the central portion of the socket into the other pocket 3 and is provided at its inner end with the usual spring terminal 7 to contact with the central terminal of the lamp. Each of the contact plates 5 and 6 are provided with clamping screws 8 adjacent to their outer ends and accessible to a screw driver through the openings at the tops of the pockets in which they are situated. Each of the plates 5 and 6 are also provided with a wire positioning flange 9 adjacent to the screw 8 and with an abutment 10, which prevents the ends of the contacting wire from either being pushed into the socket or being drawn therein as the clamping screw is tightened. Each terminal containing pocket is provided with an opening 11 of sufficient size for the insertion of the end of a supply wire, this opening being horizontal and alined with the space between the screws 8 and the flange 9. The hole and flange are so positioned with reference to the screw that when the screw is set after the insertion of the wire, its friction on the wire tends to draw the wire inwardly but the abutment 10 prevents the wire from being drawn in too far as previously explained.

It will be noted that the socket described comprises a minimum number of parts and may be cheaply constructed, that the terminals are so completely inclosed in the deep pockets that there is no possibility of arcing due to loose contact or other cause communicating fire to any adjacent inflammable material, and, further, that the contacting wires may be inserted and connected without bending the ends thereof, and the socket can, therefore, be quite easily connected and disconnected from the supply wires.

Having fully described my invention, what I claim as new and desire to secure by Letters-Patent of the United States is:

1. A receptacle for electric lamps provided with integral walls forming a lamp socket and inclosing pockets of substantial

- depth for the connecting terminals of the receptacle, said pockets being each provided with a tool receiving opening and an opening for the introduction of a current supply wire.
5. An integral receptacle for electric lamps provided with a lamp socket and a pair of terminal inclosing recesses adjacent thereto and of substantial depth, each of 10 said recesses being provided with a tool receiving opening, and a pair of conducting members each extending from the bottom of the lamp socket to the bottom of one of the recesses.
15. 3. An integral receptacle for electric lamps provided with a lamp socket and a pair of terminal inclosing recesses adjacent thereto and of substantial depth, each of 20 said recesses being provided with a tool receiving opening and with a separate opening for the introduction of a current supply wire, a pair of conducting members each extending from the bottom of the lamp socket to the bottom of one of the recesses.
25. and each provided with a clamping screw and a wire positioning flange adjacent thereto, said terminal inclosing recesses each having a horizontally positioned opening in alinement with the space between the clamp-
- ing screw and flange for the insertion of a 30 current supply wire.
4. A receptacle for electric lamps having a lamp receiving socket and a pair of pockets adjacent thereto, and socket connecting terminals inclosed in said pockets, each of 35 said pockets being provided with a tool receiving opening.
5. A receptacle for electric lamps having a lamp receiving socket, terminal inclosing pockets adjacent thereto and communicating 40 therewith at the bottom, conducting plates, each extending from the bottom of the lamp socket to the bottom of a terminal pocket and provided with a clamping screw, an abutment, and a wire positioning flange, 45 each of said pockets being provided with a tool receiving opening and a horizontally positioned opening in alinement with the space between the clamping screw and flange for the insertion of a current supply wire. 50

In testimony whereof, I have hereunto set my hand and affixed my seal in the presence of the two subscribing witnesses.

EDWIN F. GUTH. [L. s.]
